BUTADIENE SEPARATION

Karl H. Hachmuth, Bartlesville, Okla., assignor to
 Phillips Petroleum Company, a corporation of
 Delaware

Application August 10, 1942, Serial No. 454,312

4 Claims. (Cl. 202—39)

1

This invention relates to the recovery of butadiene-1,3 from a complex petroleum mixture comprising both normally gaseous and normally liquid hydrocarbons of both saturated and unsaturated linkages. More specifically, it relates to a process for recovering substantially pure butadiene-1,3 from a petroleum fraction consisting principally of propane, propylene and lighter hydrocarbons, isobutane, isobutylene, butene-1, butadiene-1,3, n-butane, butene-2 (both high and low boiling), and a heavy fraction of 5 and more carbon atoms containing a large percentage of diolefins. The invention further relates to the recovery of butadiene-1,3 from a complex petroleum fraction containing, in addition to such hydrocarbons as described above, small quantities of both methylacetylene and vinylacetylene.

One source of butadiene-1,3 is from various hydrocarbon cracking and reforming processes in which the butadiene may be recovered as a by-product from the reaction effluents. The economical recovery of substantially pure butadiene from the other reaction products presents a difficult separation problem, for a number of reasons among which are the following:

1. Butadiene is usually present in small concentrations in the reaction effluents, thereby requiring the handling of large volumes of material.

2. Many four carbon atom hydrocarbons present with the butadiene in the reaction mixture have boiling points very close to that of butadiene. For this reason, and also because of the fact that the concentration of butadiene in the reaction mixture is usually very small, extremely careful fractionation must be practiced to obtain the maximum recovery of high purity butadiene.

3. An azeotrope is formed between butadiene and n-butane. Some means other than conventional fractionation must therefore be employed to remove the butane from the butadiene if the butadiene recovery and purity are to be kept at a maximum.

4. The C₅ and heavier fraction usually contains a large percentage of diolefins, for example, cyclopentadiene, isoprene, and piperylene, which undergo non-catalytic polymerization at or above room temperature. It is advantageous, and usually essential, for reasons disclosed below to remove these materials early in the separation process.

5. Small amounts of acetylenes, principally methylacetylene and vinylacetylene, may be present in the C₄ fraction. Since any appreciable quantity of these compounds is injurious to the

2

quality of synthetic rubber manufactured from the butadiene, the separation steps used should include a provision for their removal.

Therefore, and with the above considerations in mind, the principal object of this invention is to provide an economical and practical arrangement of separation steps for the recovery of butadiene-1,3 from a complex hydrocarbon mixture such as previously described. Numerous other objects will more fully appear hereinafter.

The accompanying drawing portrays diagrammatically one arrangement of equipment which has been found useful in carrying out the present invention in one embodiment thereof.

15 My invention will first be described in connection with the preferred embodiment wherein a butadiene-containing stream which also contains C₃ hydrocarbons including methylacetylene, C₄ hydrocarbons boiling close to butadiene and including butene-2, normal butane, vinylacetylene, possibly isobutane although it may be absent, generally butene-1, generally isobutylene, usually C₅ hydrocarbons, and frequently heavier hydrocarbons than C₅.

25 The butadiene-containing feed is first subjected to a depropanizing step. This step has for its particular purpose, in addition to removal of propane and propylene, the removal of the methylacetylene which would otherwise appear as a contaminant in the butadiene. Consequently, this step is necessary whether or not the volume of C₃ hydrocarbons in the initial feed stream is large or small. If the volume of C₃ hydrocarbons in the initial feed stream is large, this step, of course, has the further advantage in that it reduces the load on subsequent equipment.

30 The extent of the removal of methylacetylene is dependent upon the extent or degree of depropanization; that is, the more complete the depropanization of the feed the more complete the removal of the methylacetylene. For example, the following tabulation gives an approximate indication of the relation between the extent of depropanization and the extent of removal of methylacetylene by a fractionator having a moderate number of trays:

50	Per cent propane removal	Per cent methylacetylene removal
	90	50.8
	95	55.3
	97	60.7
	99	68.5

It can be seen from the above tabulation that essentially complete depropanization of the feed is highly desirable to reduce the methylacetylene content to a low value. Also, it can be seen that with essentially complete propane removal, roughly 20 to 30 per cent of the methylacetylene originally present will remain in the feed. However, the amount of this component in the original feed stream to the depropanizing step is usually less than one per cent. Consequently, when 70 to 80 per cent of this one per cent of methylacetylene is removed in the depropanizing step only a small fraction remains. This small amount that remains in the bottom effluent from the depropanizing step is later removed in the absorption step.

The bottom fraction from the depropanizing step is subjected to a further fractionation which is essentially for the purpose of removing the C₈ and heavier hydrocarbons and a large portion of the butenes-2. Not all of the butenes-2 can be economically removed by fractionation because of the closeness of their boiling points (cis and trans) to those of n-butane, butadiene, butene-1, and isobutylene. Consequently, the fractionation is carried out to remove as much of the butene-2 as possible without loss of butadiene in order to reduce the load in the subsequent absorption step with furfural. The final removal of butene-2 is effected by a fractionation step after the furfural absorption and stripping steps.

As pointed out, the removal of as much of the butenes-2 as possible before the absorption step is desirable from the standpoint of reducing the load on the absorption equipment. However, since removal of all of the butenes-2 cannot be effected economically in the second fractionation step, and since a third fractionation step has to be employed after the absorbing stripping step to remove the residual butenes-2, etc., it is frequently desirable to balance the load of butenes-2 removal between these two fractionation steps rather than operating the second fractionation step before the absorption-stripping steps to remove as much of the butenes-2 as possible. Also, the second fractionation step removes some of the vinylacetylene. The residual vinylacetylene is removed in the final distillation step after the furfural absorption and stripping steps along with butene-2.

The overhead from the second fractionation step is subjected to a furfural absorption treatment which selectively absorbs butadiene and vinylacetylene to the essential exclusion of the other hydrocarbons, except butenes-2, in the stream. The butenes-2 are distributed between the overhead and bottom product. The primary purpose of this step is to separate the isobutylene and butene-1 from the butadiene. However, this step also results in an additional advantage in that removal of normal butane which forms an azeotrope with butadiene is simultaneously effected. The reason for employing this step to remove butene-1 and isobutylene is that it is difficult to fractionate these components from butadiene without losing considerable butadiene. This is because of the closeness of their boiling points to that of butadiene and the butadiene-normal butane azeotrope. Consequently, where separation by fractionation is attempted, butadiene and normal butane appear in the isobutylene-butene-1 overhead product.

For example, we have found that even a 200 plate fractionator with a reflux ratio of 150 to 1 will not remove butene-1 and isobutylene com-

pletely unless considerable butadiene is included in the butene-1-isobutylene overhead product. Obviously, this is uneconomical when as good or a better separation is possible with a furfural absorption column having only 100 trays, a hydrocarbon reflux ratio of 17 to 1, and a furfural ratio of 38 to 1. In other words, the reflux ratio is reduced about one-third and the number of trays one-half. Other advantages are also obtained with a furfural absorption system such as nearly complete recovery of butadiene and effective elimination of normal butane along with butene-1 and isobutylene which would otherwise have to be removed by some other means.

It is also to be noted that normal butane cannot be removed from butadiene by simple fractional distillation because of the azeotrope formed by these two compounds. Usually, however, normal butane represents only a comparatively small percentage of a butadiene-containing mixed hydrocarbon stream, and since the azeotrope is the minimum boiling type and, therefore, boils at a lower temperature than butadiene, it would appear that by taking slightly more butadiene overhead than required to form the azeotrope with the normal butane present, the normal butane could be eliminated from the butadiene retained in the bottom product. However, in practice the separation cannot be effected in this manner which probably means that the other components in the hydrocarbon mixture tend to partially break the azeotrope. In the previously discussed 200 plate fractionator with a reflux ratio of 150 to 1, the indications were that if about 25 per cent of the butadiene-1,3 was taken overhead with the butene-1 and isobutylene, approximately only 50 per cent of the normal butane was taken overhead. When using a furfural absorption system in accordance with my invention, the normal butane can be removed overhead along with the butene-1 and isobutylene practically 100 per cent with less than one per cent loss of butadiene. The combined amount of butene-1 and isobutylene retained in the furfural along with butadiene is usually less than one per cent.

As pointed out above, the overhead products from the second fractionation step are, in accordance with my invention, subjected to a furfural absorption treatment wherein the butadiene, vinylacetylene, and most of the butene-2 are selectively absorbed while butene-1, isobutylene, butanes, and a small portion of the butene-2 are not. However, to effect this separation it is essential that a certain amount of reboil heat be applied to the furfural absorber. Furfural is selective to varying degrees towards all of the different hydrocarbons. Those towards which it is less selective are easily stripped from it while those towards which it is most selective are more difficultly removed. The reboil heat which is applied at the bottom of the furfural absorber functions to strip out the less selectively absorbed compounds consisting, in the usual case, primarily of butene-1, isobutylene, and normal butane. The butadiene, vinylacetylene, and most of the butene-2 are retained in the furfural. Of course, to remove normal butane, isobutylene, and butene-1 essentially completely, it is necessary to strip out some butadiene in the bottom of the absorber. However, the butadiene and undesirable components after being released pass upwardly through the furfural towards the top where the furfural is cooler than at the reboiler, and the butadiene is again selectively absorbed

while the undesirable less selectively absorbed components, after the upper layers of furfural once become essentially saturated with them, are discharged overhead.

The rich furfural from the absorption step is separated from the absorbed hydrocarbons in a stripping step. The resulting lean furfural is returned to the absorption zone. The overhead products from the stripping zone are subjected to a fractional distillation to remove butene-2 and vinylacetylene from the butadiene to give essentially pure butadiene. The pure butadiene is recovered as an overhead product. Part of the purpose of this final fractionation step has already been pointed out in the discussion of the second fractionation step. It also serves to remove any furfural carried over from the stripping step and any polymer of butadiene or furfural that might be present.

Butadiene of very high purity can be obtained by my process. In plant operations, butadiene of better than 99.5 per cent purity has been obtained, namely 99.8, with about 98.5 to 99 per cent being about the average purity obtained consistently. In comparison with this, the data previously presented for the recovery of butadiene from butylenes, butanes, etc., by fractionation alone indicates that butadiene of high purity can be obtained provided normal butane is not present or its concentration in the feed stock is very low, but even so, considerable butadiene necessarily has to be wasted to effect essentially complete removal of the butylenes. However, normal butane, as well as isobutylene and butene-1, is usually present in butadiene-containing feed streams and when present in quantities equal to or less than that required to form the azeotrope with butadiene, it tends to become the limiting factor in regard to the purity of the butadiene that can be recovered by fractionation alone, because in fractionation it goes overhead with the butadiene. In concentrations higher than that required to form the azeotrope, the purity of the butadiene recovered will be approximately equal to its concentration in the azeotrope, that is, about 80 per cent.

In accordance with my invention, a predominantly C₄ stream comprising butadiene and butene-2, with or without other hydrocarbons, may be subjected to selective solvent extraction with a solvent for the butadiene under conditions such that only a portion of the butene-2 is dissolved. The rich solvent is then stripped in the usual way driving off the dissolved butadiene and butene-2. Thereupon, and this is a most important feature of this embodiment of my invention, the recovered mixture is fractionally distilled to separate essentially pure butadiene, i. e. at least 98% pure, on the one hand from the butene-2 on the other hand.

In most cases the butadiene stream will contain normal butane which has heretofore involved difficulties of separation from butadiene. Such a feed stream may be treated in accordance with my invention to readily recover the butadiene in a high state of purity, at least 98%, by first extracting with a solvent selective for butadiene whereby all the butadiene and only a portion of the butene-2 in the feed are dissolved but none or only a trace of the normal butane is dissolved. Upon stripping and fractionating as described in the preceding paragraph, pure butadiene is recovered as before.

It will be seen that the stream treated by the 75 moved. For reference purposes the boiling points

solvent extraction step is primarily or exclusively a C₄ stream. In addition to the specific C₄ hydrocarbons referred to above, namely, butadiene, normal butane and butene-2, it may contain, in amounts varying from traces up to substantial amounts, butene-1, isobutylene, and isobutane. Frequently it will contain substantial amounts of vinylacetylene which is difficult if not impossible to separate from the other components present by using conventional methods, such as fractional distillation, because of the closeness of its boiling point to that of some of the other components of the mixture, because it possibly forms azeotropes with other components of the mixture, and possibly because of its tendency to decompose or polymerize.

When proceeding in accordance with my invention, however, any vinylacetylene present in the C₄ stream being treated is dissolved, along with the butadiene, in the extraction solvent. During the fractionation of the mixture recovered by stripping the rich solvent the butadiene is readily separated overhead while the vinylacetylene is removed in the bottoms along with butene-2 if present.

The butadiene-containing C₄ stream may advantageously be prepared from any available stream containing hydrocarbons lighter and/or heavier than C₄, in accordance with a more specific aspect of my invention. For example, such a stream, which may have been produced by cracking, dehydrogenation, etc., may be first fractionated in a depropanizing step to separate C₃, methylacetylene and lighter hydrocarbons; whereupon the bottoms may be fractionated in a debutanizing operation to recover overhead all the C₄ constituents originally present except a part of the butene-2. This C₄ overhead product may then, either with or without interposition of still another fractionation to separate any isobutane present, be subjected to solvent extraction and the succeeding steps described above for the recovery of the pure butadiene.

Removal of any isobutane in the manner just alluded to further lowers the volume load on the solvent extraction step.

Frequently the original stream, except for a stream obtained by dehydrogenating C₄ hydrocarbons, before separation of the C₄ stream by depropanizing and debutanizing, will preponderantly comprise C₃ and lighter. Often these will amount to 90% or more of the original stream. However, for a stream obtained by dehydrogenation of C₄ hydrocarbons the depropanizing step is still necessary for the removal of methylacetylene.

The original stream may contain appreciable amounts of methylacetylene. This is essentially completely removed in the first fractionation step. Also the C₅ content of the stream may comprise appreciable amounts of C₅ conjugated diolefins, namely, isoprene, piperylene and cyclopentadiene. These go out as bottoms in the debutanizing step, and likewise are prevented from interfering with the operation of the process.

Isobutane, if present, may or may not have been removed from the C₄ stream subjected to the solvent extraction. This may have been effected in the depropanizing step by appropriate adjustment of the cut, or in an intermediate fractionation step as referred to above. Isobutane is the lowest boiling of the C₄ hydrocarbons apt to be encountered and therefore readily re-

of the C₃ and C₄ hydrocarbon apt to be present in the original stream are tabulated as follows:

	°C.
Propylene	-47.6
Propane	-44.1
Methylacetylene (allylene)	-23.2
Isobutane	-11.8
Isobutylene	-7.1
Butene-1	-6.3
Butadiene-1,3	-4.5
N-butane	-0.5
Butene-2 (Trans)	+0.9
Butene-2 (Cis)	+3.6
Vinylacetylene	+5.1
Ethylacetylene	+8.8
Butadiene-1,3 (biacetylene)	+9.8
Butadiene-1,2	+10.3
Dimethylacetylene	+27.2

As the selective solvent, furfural is by far the most highly preferred. However, other solvents having similar selectivity for butadiene may be used in place of furfural, though less desirable. Examples are: nitrobenzene, dichlorodiethyl ether, dimethyl formamide, methyl levulinate, glycol diacetate, diethyl acetamide, pyridine, phenol, phenol plus water, benzyl alcohol, etc.

The furfural used may be anhydrous but preferably contains up to 5% of water, usually 4 to 5%, in order to increase its selectivity for butadiene, lower its boiling point, and bring about other advantages. Use of furfural containing significant amounts of water is disclosed and claimed in my copending applications, Serial No. 430,307, filed February 10, 1942 and Serial No. 438,844, filed April 13, 1942. Since the water is lost from the system by going overhead with the hydrocarbons evolved in the stripping column, it is convenient to add water to the system from time to time or continuously. For example, this water may be introduced to the stripping column, say at the top thereof, or to the lean furfural stream fed into the top of the extraction column. It may be desirable to maintain the furfural in the system and especially in the absorber completely or substantially saturated with water at the temperatures involved.

The furfural or the like breaks any azeotrope of normal butane and butadiene or prevents the formation of such azeotrope by dissolving the butadiene. In fact the invention is applicable to an azeotrope of butadiene and normal butane. For example, such an azeotrope, which contains approximately 80% butadiene and 20% normal butane, and formed in any suitable manner, may be solvent extracted as described above preferably with furfural to recover pure butadiene.

The final fractionation to separate butadiene of at least 98.5% purity from butene-2 may advantageously be conducted in a column of preferably not less than 100 trays. The final fractionation separates out in the bottoms product any furfural or other selective solvent carried in the overhead from the stripping column.

Referring to the drawing, from a source of supply, not shown, a petroleum fraction consisting principally of propane, propylene and lighter hydrocarbons, isobutane, isobutylene, butene-1, butadiene-1,3, normal butane, butene-2 (both high and low boiling), and a C₅ and heavier fraction containing a large percentage of olefins is charged to fractionator 2 through line 1. The mixture may or may not contain detectable quantities of all of the above hydrocarbons and also may or may not contain detectable

quantities of acetylenes. Substantially all the propane, propylene and lighter hydrocarbons, which will ordinarily represent the greatest portion of the feed to fractionator 2, as well as most of any methyl-acetylene that may be present in the feed, are removed from the top of fractionator 2 through line 3. Substantially all of the C₄ and heavier hydrocarbons, along with any vinyl-acetylene that may be present in the feed, are removed from the bottom of the fractionator through line 4 and charged to fractionator 5.

In a butadiene by-product recovery plant wherein its feed consists essentially of the reaction products from a petroleum cracking and/or reforming operation, large quantities of hydrocarbons boiling below C₄'s may ordinarily be expected to be present in the charge stock to the recovery plant. Therefore, early depropanization has the advantage of lowering the volume of material to be handled throughout the rest of the separation steps thereby reducing equipment size and investment cost. This step also has the further advantage of removing the major portion of any methylacetylene that may be present in the reaction mixture and which, if not removed, will be absorbed by the lean furfural (which is employed subsequently as a selective solvent) in absorber 8; upon stripping of the rich furfural in stripper 11, the methyl acetylene will pass overhead through line 12 to fractionator 14 and will be removed overhead from this fractionator through line 15 thus appearing as an impurity in the finished butadiene product which is also withdrawn through line 15.

Fractionator 5 is operated in such a manner as to remove substantially all of the C₅'s and heavier components and part of the butene-2 from the bottom of the fractionator through line 7. The overhead product, consisting of butanes, butadiene-1,3, isobutylene, butene-1 and butene-2 along with any vinylacetylene is removed via line 6 and charged to absorber 8. Several advantages are gained by the fractionation step conducted in fractionator 5. Among these advantages are:

1. Certain of the diolefins compounds that may be present in the C₅ and heavier fraction, and especially conjugated diolefins, such as isoprene, piperylene and cyclopentadiene are quite valuable. Such diolefins hydrocarbons tend to polymerize at or above room temperatures, the polymerization rate increasing rapidly with temperature. By removing the C₅'s early in the process the time of processing them is reduced and they are not subjected to the high temperatures of the absorbing and stripping operations, thus minimizing any loss of these valuable hydrocarbons through polymerization reactions.

2. Over a period of time some of the olefinic compounds, particularly the diolefins, present in the C₅ and heavier fraction polymerize to gummy materials. Gum is not only undesirable because it deposits on heating elements causing a reduction in heat transfer or because it may deposit in lines, valves, etc., thereby reducing the flow, but also because it will be absorbed in the furfural thus making its regeneration more difficult. Thus by early removal of the C₅ and heavier, the extent of gum formation is markedly reduced.

3. Removal of the heavier material early in the process lowers subsequent stripping and fractionation temperatures thereby reducing the loss of butadiene by polymerization.

4. A further advantage obtained by the use of fractionator 5 is that the load on the absorbing

and stripping column is reduced. This is because the C₅ and heavier fraction and a considerable part of the butenes-2 are removed with the bottom product without entailing any loss of butadiene.

The overhead product from fractionator 5 is charged to absorber 8 through line 6. In this column lean furfural is introduced through line 13 and employed as a selective solvent to obtain an extract consisting of a mixture of butadiene and butene-2 relatively free from butanes, isobutylene, and butene-1. A conventional re-boiling coil 8A is employed in the bottom of absorber 8 to give a cleaner separation therein, in accordance with principles now well-known to the art. Rich furfural containing substantially all of the butadiene charged to the absorber plus some butene-2 and any vinylacetylene that may be present is withdrawn from the bottom of the absorber through line 10 and charged to stripper 11 equipped with heating coil 11A. The product withdrawn from the top of absorber 8 contains substantially all of the isobutylene, butene-1 and butanes in the feed to the absorber plus some of the butene-2 as well as any propane that may have been retained in the product withdrawn from the bottom of fractionator 2.

In column 11 the rich furfural is stripped of butadiene, butene-2 and vinylacetylene, if present. These hydrocarbons pass overhead through line 12 to fractionator 14. The lean furfural is withdrawn from the bottom of the stripper through line 13 and is recycled to absorber 8. Since n-butane and butadiene form an azeotrope, pure butadiene can not be obtained by conventional fractionation. By my use of solvent extraction to separate the butadiene from the n-butane at this stage in the process, these difficulties are completely overcome in a simple and economical manner.

In the final fractionation, the butadiene, butene-2 and vinylacetylene, if any, are charged to fractionator 14 through line 12; substantially pure butadiene is removed overhead through line 15 and the butene-2 and any vinylacetylene, plus any small amounts of furfural and polymer of butadiene or furfural that may have carried over from the stripper column 11, are removed from the bottom of fractionator 14 through line 16.

Butadiene may be separated from admixture with normal butane in azeotropic or any other proportions and with or without other hydrocarbons which may be close-boiling or not, by selective solvent extraction with a solvent which is selective for butadiene but which does not appreciably dissolve normal butane. Upon stripping of the butadiene-rich solvent there is obtained butadiene free from normal butane and the formation of an azeotrope of the butadiene with the normal butane, which occurs when efforts are made to separate by fractional distillation a mixture comprising these two ingredients, is effectively prevented.

Example

As an example of the operation of my invention, an unsaturated petroleum fraction, from a source not shown, containing about 95 per cent propane, propylene and lighter hydrocarbons and 5 per cent of C₄ and heavier hydrocarbons was charged through line 1 to fractionator 2 which was operated at a pressure of 115 pounds per square inch absolute, a reflux ratio of 0.75:1, a tower top temperature of 30° F. and a tower

bottom temperature of 175° F. Substantially all of the C₃'s and lighter hydrocarbons, consisting of about 70 parts of propane and propylene, 30 parts of ethane and ethylene and a trace of methane and methylacetylene were removed overhead through line 3. Substantially all of the C₄ and heavier hydrocarbons, consisting of about 32 parts butadiene, 7 parts butene-1, 3 parts isobutylene, 12 parts butene-2 (both high and low boiling), 2 parts butane, and 44 parts of C₅ and higher along with a small quantity of vinylacetylene were withdrawn from the bottom of fractionator 2 through line 4 and charged to fractionator 5.

From fractionator 5, which was operated at 70 pounds per square inch absolute, reflux ratio of 25:1, top temperature of 103° F. and bottom temperature of 220° F., all of the C₅ and heavier material and about one-half of the butene-2 was removed from the kettle. The overhead product, consisting of about 3 parts propane, 63 parts butadiene, 13 parts butene-1, 5 parts isobutylene, 13 parts butene-2, and 3 parts of butane along with a trace of vinylacetylene was charged to absorber 8.

Lean furfural from stripper 11 was introduced into absorber 8 through line 13. Rich furfural, containing principally about 4 parts of butadiene and 0.3 part of butene-2 (both high and low boiling) along with a trace of C₅₊ and vinylacetylene was withdrawn from the bottom of absorber 8 through line 10 and charged to stripper 11. The product withdrawn from the top of absorber 8 through line 9 contained about 45 parts of butene-1, 10 parts of propane, 17 parts isobutylene, 17 parts of butene-2 (mostly low boiling) and 11 parts butane. The absorber was operated at a pressure of 65 pounds per square inch absolute, reflux ratio of 16.6:1, top temperature of 120° F. and bottom temperature of 240° F.

The rich furfural was introduced into stripper 11 through line 10. The stripper was operated at a pressure of 65 pounds per square inch absolute, reflux ratio of 1:1, top temperature of 103° F. and bottom temperature of 300° F. Lean furfural containing 99.9 per cent furfural and 0.1 per cent C₅'s was withdrawn from the bottom of the stripper through line 13 and recycled to absorber 8. The stripper overhead product, consisting of 93 parts butadiene and 7 parts of butene-2 along with traces of isobutylene, butene-1, C₅₊, vinylacetylene and furfural was charged to fractionator 14 through line 12.

In the final fractionator 14, operated at 65 pounds per square inch absolute, reflux ratio of 14:1, top and bottom temperatures of 103° and 105° F., respectively, a finished butadiene product of about 98.5 per cent purity was withdrawn overhead through line 15. The bottoms product withdrawn from line 16 consisted of about 97 parts butene-2, 1 part butadiene, and 2 parts of C₅ and heavier, furfural and vinylacetylene.

From the foregoing description a great many advantages of my invention will be apparent to those skilled in the art. Many of these have been referred to in detail above. Many of the quantitative advantages will not be discussed in great detail because of the complexity of the calculations involved. Among the more general qualitative advantages are the following. The invention makes possible a clean separation of butadiene from normal butane which has not heretofore been possible to the best of my knowledge. The unique combination of solvent extraction fol-

lowed by fractionation in the manner described in detail makes possible the clean separation of extremely pure butadiene. The invention enables the complete separation of vinylacetylene from the butadiene which should be free from vinylacetylene to be acceptable as a starting material in synthetic rubber production. The invention also makes possible starting with a crude broad cracking, refinery, or dehydrogenation stream and enables ready elimination of the C₃ and lighter including objectionable methylacetylene and of the C₅ and heavier including objectionable C₅ diolefins together with a substantial portion of the butene-2 which is found in the bottoms from the second fractionator 5. Initial removal of all these materials lightens the load on the solvent extraction unit and prevents interference with subsequent steps in the process. Also this removal contributes materially to the high purity of the product obtained. Moreover the invention enables one to readily and economically obtain maximum yields of butadiene even though the concentration in the C₄ stream is low and though the original concentration in the initial composite feed is extremely low. A great many more advantages will be readily apparent to those skilled in the art.

By the terms "fractionation" and "fractionating" as used herein and in the claims, I mean fractional distillation. As used herein "butadiene" means butadiene-1,3. The terms "butene-2" and "butenes-2" mean both the low and high boiling isomers.

I claim:

1. A process for the recovery of butadiene from a mixture of hydrocarbons comprising butadiene and other closely-boiling C₄ hydrocarbons including butene-1 and butene-2 which comprises sub-

jecting said mixture to a first fractional distillation effecting removal of a portion of the butene-2, subjecting the remainder of said mixture to selective solvent extraction with a solvent which is selective for butadiene under conditions such that a fraction consisting essentially of butadiene and a further portion of the butene-2 is absorbed without substantial absorption of the butene-1 and the remainder of the butene-2, stripping said fraction of butadiene and butene-2 from the solvent, and subjecting said fraction to a second fractional distillation effecting separation of the butadiene from the butene-2.

2. A process as defined in claim 1 wherein said solvent is furfural.

3. A process for the recovery of butadiene from a mixture of hydrocarbons comprising butadiene and other closely-boiling C₄ hydrocarbons including normal butane, butene-1, and vinylacetylene, which comprises subjecting said mixture to a first fractional distillation effecting removal of a portion of the butene-2; subjecting the remainder of said mixture to selective solvent extraction with a solvent which is selective for butadiene under conditions such that a fraction consisting essentially of butadiene, vinylacetylene, and a further portion of the butene-2 is adsorbed without substantial adsorption of the butene-1 and the remainder of the butene-2; stripping said fraction of butadiene, vinylacetylene, and butene-2 from the solvent; and subjecting said fraction to a second fractional distillation effecting separation of the butadiene from the vinylacetylene and butene-2.

35 4. A process as defined in claim 3 wherein said solvent is furfural.

KARL H. HACHMUTH.
